UNITED STATES PATENT OFFICE.

FREDERICK SCHAEFER, OF BOSTON, MASSACHUSETTS.

INCANDESCENT ELECTRIC LAMP.

SPECIFICATION forming part of Letters Patent No. 352,006, dated November 2, 1886.

Application filed March 11, 1886. Serial No. 194,832. (No model.)

To all whom it may concern:

Be it known that I, FREDERICK SCHAEFER, of Boston, county of Suffolk, and State of Massachusetts, have invented an Improvement in 5 Incandescent Electric Lamps, of which the following description, in connection with the accompanying drawings, is a specification, like letters on the drawings representing like parts.

This invention relates to and is an improvement on that class of incandescent electric lamps shown and described in United States application Serial No. 179,601, dated October 12, 1885, and has for its object to provide said lamp with means to stop the rotation of the 10 lamp proper within its holder, to thereby permit short-circuiting of said lamp.

The peculiar features wherein this invention consists will be hereinafter pointed out in the claims at the end of this specification.

20 Figure 1 is a vertical section of a complete incandescent electric lamp embodying my invention; Fig. 2, a section of Fig. 1 on line $x-x$ with the shade removed; Fig. 3, a side elevation of the insulating-disk partially broken out, the key being removed; Fig. 4, a view of Fig. 3, looking upward; and Figs. 5 and 6, details to be referred to.

The bulb A, containing the carbon filament a and platinum electrodes a' a'', is embedded 30 in the plaster-of-paris mold a³, in which are secured the terminal lugs a⁴ a⁵, to which the platinum electrodes are attached. The mold a³ is surrounded by the metal band b, provided with the pins or projections b' b'', which enter 35 slots b' b'' (see Fig. 2) in the shell or casing B of the holder, and are rotated in a groove, b⁵, in said casing or shell. The shell or casing B contains within it the spring d, the disk d', of insulating material, separated from said spring 40 by a washer, d², of insulating material, said insulating-disk being slotted at d³ (see Figs. 3 and 4) to receive a key, d^x, by rotating which the lamp may be placed in and cut out of circuit, as desired.

45 The insulating-disk d' has secured to one of its faces, by screws d⁴ d⁵, contact-pieces e e', each of said contact-pieces being provided with an outturned flange, e², said flanges being preferably in the same diametrical line, as 50 shown in Fig. 4, the contact-piece e' being extended over the slot d³, the screw d⁵ being con-

nected to one line-wire by the wire e⁴. The wire f, which is connected to the second line-wire, is secured to the screw f', extended through the insulating-disk d', and screwed 55 into a metallic ring, f², (see Fig. 3,) secured to the opposite face of the disk d', the said metallic ring being upset, as at f⁴.

The key d^x is composed of a metal collar, h', having insulation h, (see Fig. 6,) the metal part 60 of said collar having a shank, h², on which is secured a handle, h³, the insulation being provided with a groove, 2, and the metal with a groove, 3.

The collar referred to is designed to enter 65 the slot d³ and to be rotated therein by turning the handle h³, and the said collar is locked and maintained in position within said slot by the upset portion f⁴ of the metallic ring f², which enters one of the grooves 2 3, referred to, according as the lamp is in or out of circuit, and also by means of washers h⁵ h⁶, which are mounted on the shank h² of said collar, and which act frictionally, to further lock and maintain said collar in position, said 70 washers being one on the inside and the other on the outside of the shell or casing B, as shown in Fig. 1.

When it is desired to place the lamp in circuit, the handle h³ is turned so as to have the 80 metal portion h' of the collar engaged by the contact-piece e' on one side and by the metal ring f² on the other side, the upset portion f⁴ of said ring entering the groove 3 and locking the key d^x until positively moved. 85

With the lamp in circuit, the current enters the lamp by wire e⁴ to the contact-piece e, from contact-piece e through the filament a to contact-piece e', from contact-piece e' to the metallic ring f² by the metal portion h' of the collar, 90 and from the metal ring f² to the wire f by screw f'.

The manner of completing the circuit in the lamp as just described is especially advantageous in this class of incandescent electric 95 lamps. When the lamp proper is connected to its holder, all danger of short-circuiting of said lamp is obviated by means of the upturned flanges e², which limit the rotation of the lamp in its holder.

In Fig. 5 I have shown a shade, g, partially broken off, and provided with a collar, g', hav-

ing grooves g^2 g^3 , by means of which said shade is placed upon the lamp; but said shade is not herein claimed, as it forms the subject-matter of another application filed concurrently herewith, Serial No. 194,833.

I claim—

1. In an incandescent electric lamp, the bulb A, the mold to hold said bulb, and terminal lugs a^4 a^5 , incased in said mold, combined with the insulating disk d' , having contact-pieces e e' secured thereto, and provided with outwardly-turned flanges e^2 , to be engaged by said lugs, to thereby prevent said lamp from being short-circuited, substantially as described.
2. In an incandescent electric lamp, the in-

sulating disk d' , provided on one face with the metal ring f^2 , upset as at f^4 , and having contact-pieces e e' secured to its opposite face, combined with the key d^x , composed of a metal collar, h' , having insulation h , and with the screw f' , secured to the metal ring f^2 , and by which the current is conducted to the line-wire, substantially as described.

In testimony whereof I have signed my name to this specification in the presence of two subscribing witnesses.

FREDERICK SCHAEFER.
